Attorney

UNITED STATES PATENT OFFICE

GEORGE A. McDONNELL, OF EVERETT, MASSACHUSETTS

BEDCLOTHES HOLDER

Application filed November 3, 1928. Serial No. 317,070.

My invention relates to bed clothes fasteners and means for securing such a device in place. It has for its purposes, to provide a device easily attachable to the frame 5 of the spring or the bed upon which the clothes are to be held; to provide a device of minimum parts, simple and inexpensive construction, easily attachable and detachable, and affording protection to the clothes 10 when fastened by means of the free moving pivotal disc G.

I accomplish the objects of my invention as shown in the accompanying drawings, which form a part of this specification and 15 in which Figure 1 shows a top view of my device attached to the frame of a bed of which a section is shown. Figure 2 shows a perspective view of the same. Figure 3 is a perspective view showing the bed clothes 20 secured in position by my device.

Referring again to the drawings A shows the main body portion of my device. B shows that portion of the body portion which fits on the inner side of the bed or spring 25 frame C. D shows the thumbscrew by which the device is secured to the frame. E shows the extension arm, projecting from the body portion B, and carrying the thumbscrew F on the thread end of which is pivotally 30 mounted the disc G adaptable to engage and hold when tightened the bed clothes H against the frame C.

Throughout the detail description and on the several figures of the drawing, similar 35 parts are referred to by like reference characters.

The accompanying drawing illustrates one complete example of the embodiment of the invention constructed according to the best 40 modes I have so far devised for the practical application of the principle.

It is obvious that those skilled in the art, 45 may vary the details of construction and arrangement of parts without departing from the spirit of my invention. I therefore do

not limit myself to the above disclosure except in so far as is necessary in construing the following claim.

Having thus described my invention I claim as new and desire to secure by Letters 50 Patent of the United States of America:

A bed clothes fastener comprising a body portion shaped to engage the frame of a bed or spring, a thumbscrew for engaging said frame, said body portion being provided with 55 an outwardly extending arm portion, a thumbscrew mounted at the outer end of said arm portion, and a disc pivotally mounted on the thread end of last said thumbscrew adaptable when tightened to press against 60 and hold bed clothes against said frame.

In testimony whereof I affix my signature.
GEORGE A. McDONNELL.
